[57] **CLAIM**

The ornamental design for an identification tag, as shown and described.

DESCRIPTION

FIG. 1 is a perspective view of an identification tag, showing my new design;

FIG. 2 is a front elevational view thereof;

FIG. 3 is a rear elevational view thereof;

FIG. 4 is a right side elevational view thereof, the left side elevational view being substantially a mirror image thereof;

FIG. 5 is a top plan view thereof;

FIG. 6 is a bottom plan view thereof;

FIG. 7 is a front elevational view of a second embodiment of the identification tag shown in FIG. 1;

FIG. 8 is a rear elevational view thereof; and

FIG. 9 is a right side elevational view thereof.

The top plan view and bottom plan view, FIGS. 5 and 6 respectively, are substantially identical in the alternate embodiment.
